UNITED STATES PATENT OFFICE.

GEORGE C. BOWLES, OF DETROIT, MICHIGAN.

DESIGN FOR A SCRAPER.

SPECIFICATION forming part of Design No. 32,484, dated April 10, 1900.

Application filed March 12, 1900. Serial No. 8,405. Term of patent 14 years.

To all whom it may concern:

Be it known that I, GEORGE C. BOWLES, a citizen of the United States, residing at Detroit, in the county of Wayne and State of Michigan, have invented a certain new and useful Design for a Scraper, of which the following is a specification, reference being had therein to the accompanying drawings, in which—

10 Figure 1 is a side elevation. Fig. 2 is an end elevation, and Fig. 3 is a perspective view.

The body of the scraper is of a wedge-shaped cross-section, the edges A and B, respectively, 15 forming the apex and base of the wedge being substantially parallel. One end C of the body is curved, and the opposite end D is in-

clined to the edges A and B, so as to form an acute angle with the former and an obtuse angle with the latter. 20

The leading feature of the design is the body of wedge-shaped cross-section having one end inclined to form an acute angle with the apex edge.

What I claim as my invention is—

25 The design for a scraper substantially as herein shown and described.

In testimony whereof I affix my signature in presence of two witnesses.

GEORGE C. BOWLES.

Witnesses:

M. B. O'DOGHERTY,
H. C. SMITH.
